[57] CLAIM

The ornamental design for a bar sink faucet, as shown and described.

DESCRIPTION

FIG. 1 is a front elevational view of a bar sink faucet embodying my new design;

FIG. 2 is a right side elevational view thereof;

FIG. 3 is a rear elevational view thereof;

FIG. 4 is a left side elevational view thereof;

FIG. 5 is a top plan view thereof;

FIG. 6 is a right side elevational view of a modified form of the bar sink faucet shown in FIG. 1, the left side being a mirror image of the right side shown;

FIG. 7 is a front elevational view of FIG. 6;

FIG. 8 is a top plan view of FIG. 6;

FIG. 9 is a right side elevational view of a second modified form of the bar sink faucet shown in FIG. 1, the left side being a mirror image of the right side shown;

FIG. 10 is a top plan view of FIG. 9; and

FIG. 11 is a front elevational view of FIG. 9.
